UNITED STATES PATENT OFFICE

HENRY JOSEPH ROUND, OF LONDON, ENGLAND, ASSIGNOR TO MARCONI'S WIRELESS TELEGRAPH COMPANY LIMITED, OF LONDON, ENGLAND

SOUND RECORDING APPARATUS AND ARRANGEMENT FOR USE THEREWITH

Application filed January 28, 1931, Serial No. 511,906, and in Great Britain January 23, 1930.

This invention relates to sound recording systems and more particularly to systems for recording sound on films.

The invention has for its principal object to provide a recording oscillograph or the like which cannot easily be over-loaded and which is especially adapted for producing upon a film an accurate sound record, and which shall be sensitive but not easily over-loaded and capable of dealing satisfactorily with widely varying amplitudes.

According to this invention, a moving iron oscillograph for use in sound recording comprises a moving member consisting of a small steel or similar spring reed rigidly carried at or near one end by a comparatively large block of metal and carrying a relatively stiff block of magnetic material upon which is mounted a mirror, the free spring length where bending takes place being small (of the order of about $\frac{1}{2}$ mm. to about 1 mm.) so that in use the movement of the mirror is largely rotary and said armature being damped to prevent excessive amplitude at resonance by means of small rubber or like block carried at or near the free end thereof.

Preferably means are provided for adjusting the polarizing magnetization of the oscillograph so that the response of the armature for amplitudes exceeding the minimum amplitude shall be as linear as possible.

My invention will be more clearly understood from the following specification by reference to the accompanying drawings which illustrate one form of oscillograph according to my invention and wherein:

Fig. 1 is a characteristic curve explanatory of the principle of operation of the oscillograph of my invention; Fig. 2 shows the block, reed mirror and damping arrangements for the oscillograph; Fig. 3 shows in schematic form the general arrangements of the magnetic circuit of the oscillograph; Fig. 4 shows in schematic perspective view the block, reed, mirror and damping arrangements in association with the magnetic system of the oscillograph; (in Fig. 4 approximately only half of the magnetic system is shown for the sake of clarity in the figure)

and Figs. 5 and 6 show circuit diagrams for the oscillograph of my invention.

Referring to the accompany drawings, and more particularly to Figs. 2, 3 and 4 thereof, the oscillograph comprises a main moving member consisting of an armature or reed 1 of steel or other resilient material, to which is fixed a block 8 of magnetic material which should be sufficiently thick to resist bending, and on this block is arranged a mirror 10 and a spike 4, the latter being made in the case shown as an extension of the block 8 and in one piece therewith the reed 1 is rigidly attached at or near one end to a comparatively large block 2 of metal.

The following are dimensions which have been successfully employed in practice:—

Width of spring armature 1 about 2 millimeters; free spring length where bending takes place about $\frac{1}{2}$ mm.; block 8 of magnetic material $\frac{1}{2}$ mm. thick, 2 mm. wide and $1\frac{1}{2}$ mm. with spike extension as illustrated, the spike being about 2 mm. long.

A rubber damping block 3 is firmly stuck on to the spike 4. Said block may be about 5 mm. to 1 mm. cube, the dimensions being not very important over a wide range of size.

The reed system (inclusive of the mirror) may, in most cases, be so made as to have a period at about 6,500 cycles per second, but in certain cases, where sensitiveness is of great importance, the value may be reduced as low as 4,500 cycles.

The mirror is attached to a non-bending portion of the moving member (to the block 8) and this prevents distortion of the reflected image.

The moving system thus mounted and damped is associated with a single or multi-pole magnet, and subjected to permanent or electromagnetism in a manner well known per se. In the example illustrated, the magnetic system consists of a main magnet frame 5, on which is mounted a polarizing coil 6 and which carries pole pieces 7-7 preferably shaped as shown and positioned so as to cooperate with the reed which carries an iron pole 8. On the pole pieces 7-7 are mounted operating coils 9-9 to which the currents or voltages intended to be recorded are fed. The

magnetic system including the pole pieces may be made of a high permeability iron such as that known under the registered trade mark "Numetal" or one of the recently discovered nickel-iron high permeability metals and gaps of non-magnetic material may be inserted between the pole pieces 7-7 and the remainder of the magnetizing circuit, the poles themselves being kept to as small a length as possible.

An instrument as above described will have a characteristic which consists of a line which is approximately straight for the middle portion of its length and curved at the two ends, the two curved ends corresponding to the conditions of low magnetization and approximate saturation. Such a characteristic curve is shown in Fig. 1 of the accompanying drawings, in which curve the ordinates are units of deflection (D) and the abscissae units of polarization magnetization (PC). The instrument should be operated over the middle or approximately straight portion of the characteristic with amplitudes which are not sufficiently large to "swing" into the curved portions; i. e. referring to Fig. 1, the central operating point should be point P on the curve and the operating amplitudes should lie roughly between the parallel broken lines L-L.

The gaps of non-magnetic material are shown at 11-11 and may conveniently consist of interposed brass pieces. This arrangement minimizes the effect known as "zero wandering" i. e. the tendency for the moving member not always to return exactly to the same zero position upon the cessation of current through the operating coils. The small mirror 10 may be utilized in any well known way for effecting recording.

A comparatively large mirror may be employed in an arrangement as above described since the mirror can be a large proportion of the weight of the moving part of the armature.

Glass mirrors of 3 mm. by 1½ mm. by .4 mm. thick have been successfully employed in practice. It is found that mirrors of approximately these dimensions are such that to change one mirror for another in a device as above described does not result in any serious alteration of the natural period providing the mirrors interchanged are approximately the same size.

An oscillograph as above described gives a very uniform amplitude response plotted against operating current over the frequency range up to the resonant point.

Electric currents corresponding to sound and obtained from an amplifier associated with a microphone are fed to the operating coils so as to induce corresponding vibrations in the moving member. A "slot" of intense light obtained in any convenient manner is projected on the mirror carried by the mov-

ing member and reflected therefrom to fall upon a moving photographic film surface.

The current fed through the energizing coils is first passed through an electrical network so that the amplitude of the vibrations of the armature will be approximately the same for a given microphone output at any frequency within the audible frequency range. This requirement is approximately obtained when the current through the coil of the network is approximately proportional to the grid potential applied to the last valves (i. e. the power valves) of the thermionic amplifier which is controlled from the microphone and whose output is fed to the coil and network. A preferred method of obtaining this required "constancy of current" consists in constituting the network by a series resistance shunted by a condenser so as effectively to balance out the self-inductance of the coil. Circuit arrangements suitable for accomplishing this desired result are shown in Figures 5 and 6. In these figures C represents capacity, L inductance and R resistance while the operating coils of the oscillograph are diagrammatically represented at OC. Alternatively the operating coils may be made part of a low pass filter circuit adapted to give constant current.

It is of importance to be able to set the polarizing magnetism exactly, in oscillographs of the kind in question and where electro-magnetic polarization is employed this may be effected by adjusting the current in the polarizing windings. Where permanent magnets are employed it is useful to provide a magnetic shunt arrangement and/or an air gap adjustment between the poles and the magnet for the purpose of obtaining correct magnetic setting.

What I claim is:—

1. A moving iron instrument for use in sound recording and including a moving member consisting of a small spring reed rigidly carried adjacent one end by a relatively large block of metal, a relatively stiff block of magnetic material carried on said spring reed, a mirror surface upon said last mentioned block for reflecting light rays and a small block of resilient material mounted upon said spring reed adjacent the free end thereof for damping excessive amplitude at resonance, the free spring length of said spring reed where bending takes place being relatively small and of the order of ½ mm. to about 1 mm. and means for magnetically controlling the movement of said moving member in accordance with sound vibrations.

2. A moving iron instrument for use in sound recording and including a moving member consisting of a small steel spring reed rigidly carried adjacent one end by a relatively large block of metal, a relatively stiff block of magnetic material carried on

said spring reed, a mirror surface upon said last mentioned block for reflecting light rays and a small block of rubber mounted upon said spring reed adjacent the free end thereof to damp excessive amplitude at resonance, the free spring length of said spring reed where bending takes place being of the order of $\frac{1}{2}$ mm. to about 1 mm. and means for magnetically controlling the movement of said moving member in accordance with 10 sound vibrations.

3. A moving iron instrument for use in sound recording and including a moving member consisting of a small spring reed rigidly carried adjacent one end by a relatively large block of metal, a relatively stiff block of magnetic material carried on said spring reed, a mirror surface upon said last mentioned block for reflecting light rays, a 15 small block of resilient material mounted upon said spring reed adjacent the free end thereof to damp excessive amplitude at resonance, the free spring length of said spring reed where bending takes place being of the order of $\frac{1}{2}$ mm. to about 1 mm., a magnetic polarization system means for adjusting the 20 polarizing magnetism thereof and means for magnetically controlling the movement of said moving member in accordance with sound vibrations.

4. A moving iron instrument for use in sound recording and including a moving member consisting of a small steel spring reed rigidly carried adjacent one end by a relatively large block of metal, a relatively stiff block of magnetic material carried on 35 said spring reed, a mirror surface upon said last mentioned block for reflecting light rays, a small block of rubber mounted upon said 40 spring reed adjacent the free end thereof to damp excessive amplitude at resonance, the free spring length of said spring reed where bending takes place being of the order of $\frac{1}{2}$ mm. to about 1 mm., a magnetic polarization 45 system means for adjusting the polarizing magnetism thereof and means for magnetically controlling the movement of said moving member in accordance with sound vibrations.

5. A moving iron instrument for use in sound recording and including a moving member dimensioned and adjusted to have its natural period above 4500 cycles per second and consisting of a small spring reed rigidly carried adjacent one end by a relatively large block of metal, a relatively stiff block of magnetic material carried on said 55 spring reed, a mirror surface upon said last mentioned block for reflecting light rays and a small block of resilient material mounted upon said spring reed adjacent the free end thereof to damp excessive amplitude at resonance, the free spring length of said spring reed where bending takes place being of the order of $\frac{1}{2}$ mm. to about 1 mm. and means

for magnetically controlling the movement of said moving member in accordance with sound vibrations.

6. A moving iron instrument for use in sound recording and including a moving member dimensioned and adjusted to have its natural period above 4500 cycles per second and consisting of a small steel spring reed rigidly carried adjacent one end by a relatively large block of metal, a relatively 70 stiff block of magnetic material carried on said spring reed, a mirror surface upon said last mentioned block for reflecting light rays, a small block of rubber mounted upon said spring reed adjacent the free end thereof to damp excessive amplitude at resonance, the free spring length of said spring reed where bending takes places being of the order of $\frac{1}{2}$ mm. to about 1 mm., a magnetic 75 polarization system means for adjusting the polarizing magnetism thereof and means for magnetically controlling the movement of said moving member in accordance with sound vibrations.

7. A moving iron instrument for use in sound recording and including a moving member consisting of a small steel spring reed rigidly carried adjacent one end by a relatively large block of metal, a relatively 80 stiff block of magnetic material carried on said spring reed, a mirror surface upon said last mentioned block for reflecting light rays, a spike carried by said reed and a small block of rubber fixed upon said spring reed adjacent the free end thereof to damp excessive 85 amplitude at reasonance, the free spring length of said spring reed where bending takes place being of the order of $\frac{1}{2}$ mm. to about 1 mm. and means for magnetically controlling the movement of said moving member in accordance with sound vibrations.

8. A moving iron instrument for use in sound recording and including a moving member dimensioned and adjusted to have its natural period above 4500 cycles per second and consisting of a small steel spring reed rigidly carried adjacent one end by a relatively large block of metal, a relatively 90 stiff block of magnetic material carried on said spring reed, a mirror surface upon said last mentioned block for reflecting light rays, a spike carried by said reed, a small block of rubber mounted upon said spike for damping excessive amplitude of said block of magnetic material at resonance, the free 95 spring length of said spring reed where bending takes place being of the order of $\frac{1}{2}$ mm. to about 1 mm., a magnetic polarization system means for adjusting the polarizing magnetism thereof and means for magnetically 100 controlling the movement of said moving member in accordance with sound vibrations.

9. A moving iron instrument for use in sound recording and including a moving member consisting of a small spring reed

- rigidly carried adjacent one end by a relatively large block of metal, a relatively stiff block of magnetic material carried on said spring reed, a mirror surface upon said last mentioned block for reflecting light rays, a small block of resilient material mounted upon said spring reed adjacent the free end thereof to damp excessive amplitude at resonance, the free spring length of said spring reed where bending takes place being of the order of $\frac{1}{2}$ mm. to about 1 mm., a magnetic system including gaps or spacing in the magnetic path thereof and means connected with said magnetic system for controlling the effect thereof upon said moving member.
10. A moving iron instrument for use in sound recording and including a moving member consisting of a small spring reed rigidly carried adjacent one end by a relatively large block of metal, a relatively stiff block of magnetic material carried on said spring reed, a mirror surface upon said last mentioned block for reflecting light rays, a small block of resilient material mounted upon said spring reed adjacent the free end thereof to damp excessive amplitude at resonance, the free spring length of said spring reed where bending takes place being of the order of $\frac{1}{2}$ mm. to about 1 mm., a magnetic system including gaps or spacing in the magnetic path thereof and means connected with said magnetic system for controlling the effect thereof upon said moving member.
11. A moving iron instrument for use in sound recording and including a moving member consisting of a small spring reed rigidly carried adjacent one end by a relatively large block of metal, a relatively stiff block of magnetic material carried on said spring reed, a mirror surface upon said last mentioned block for reflecting light rays, a small block of resilient material mounted upon said spring reed adjacent the free end thereof to damp excessive amplitude at resonance, the free spring length of said spring reed where bending takes place being of the order of $\frac{1}{2}$ mm. to about 1 mm., a magnetic system including gaps or spacing in the magnetic path thereof and means connected with said magnetic system for controlling the effect thereof upon said moving member.
12. In combination, a moving iron instrument for use in sound recording and including an operating coil, a moving member consisting of a small spring reed rigidly carried adjacent one end by a relatively large block of metal, a relatively stiff block of magnetic material carried on said spring reed, a mirror surface upon said last mentioned block for reflecting light rays, a small block of resilient material mounted upon said spring reed adjacent the free end thereof to damp excessive amplitude at resonance, the free spring length of said spring reed where bending

takes place being of the order of $\frac{1}{2}$ mm. to about 1 mm., an electrical network arranged to balance out the self inductance of said coil and a sound control circuit connected with said network.

13. In combination, a moving iron instrument for use in sound recording and including operating coils, a moving member consisting of a small spring reed rigidly carried adjacent one end by a relatively large block of metal, a relatively stiff block of magnetic material carried on said spring reed, a mirror surface upon said last mentioned block for reflecting light rays, a small block of resilient material mounted upon said spring reed adjacent the free end thereof to damp excessive amplitude at resonance, the free spring length of said spring reed where bending takes place being of the order of $\frac{1}{2}$ mm. to about 1 mm., a magnetic system including gaps or spacing in the magnetic path thereof and means connected with said magnetic system for controlling the effect thereof upon said moving member.

14. In combination, a moving iron instrument for use in sound recording and including an operating coil, a moving member consisting of a small spring reed rigidly carried adjacent one end by a relatively large block of metal, a relatively stiff block of magnetic material carried on said spring reed, a mirror surface upon said last mentioned block for reflecting light rays and a small block of resilient material mounted upon said spring reed adjacent the free end thereof to damp excessive amplitude at resonance, the free spring length of said spring reed where bending takes place being of the order of $\frac{1}{2}$ mm. to about 1 mm., an electrical network connected with said operating coil and a sound control circuit connected with said network, said electrical network being proportioned for balancing out the self inductance of said operating coil.

In testimony that I claim the foregoing as my invention I have signed my name this 16th day of January, 1931.

HENRY JOSEPH ROUND.
